UNITED STATES PATENT OFFICE

EDWIN B. WHEELER, OF NEW LONDON, CONNECTICUT

WELDED SHIP

Application filed November 28, 1928. Serial No. 322,321.

This invention relates to ship construction, and more particularly to the construction of welded ships.

One of the main objects of my invention is to provide a hull structure in which the elements can be readily assembled and secured together by welding. By welding the elements of the hull together I eliminate riveting, thus dispensing with the laying off, 10 punching, drilling, reaming and countersinking of thousands of rivet holes, which is encountered in constructing metal ship hulls in accordance with present practice. It is possible, by my construction, to quickly assemble 15 the hull structure and apply the plates thereto and to effect a material saving in time and labor, as well as material over the present types of hull construction. Further objects and advantages of my invention will 20 appear from the detailed description.

In the drawings:

Fig. 1 is a perspective side view of a ship hull constructed in accordance with my invention, parts of the covering and deck plates being omitted.

Fig. 2 is a section taken substantially on line 2—2 of Fig. 1.

Fig. 3 is a section taken substantially on line 3—3 of Fig. 1.

Fig. 4 is a section taken substantially on line 4—4 of Fig. 1.

Fig. 5 is a fragmentary section, on an enlarged scale, taken at the juncture of the deck and the side of the hull illustrating the method of clamping the plates for welding.

Fig. 6 is a side view of the structure illustrated in Fig. 5.

Fig. 7 is a fragmentary sectional view, on an enlarged scale, taken transversely of the hull adjacent one of the lower angles of one of the belt frames illustrating the method of clamping the plates for welding.

In constructing a ship hull in accordance with my invention I provide a plurality of belt frames 1 disposed transversely of the hull and spaced apart longitudinally thereof. Each of these frames is bounded by straight lines disposed in angular relation and defining an irregular polygon.

The frames 1 may be constructed in any

suitable manner but are preferably built up of steel plates in a known manner. Each frame is provided, in its outer edge, with notches at certain of the angles thereof. The frames are so shaped and the notches are so disposed as to give the desired contour to the hull. As will be appreciated from Fig. 1, the frames vary somewhat in shape, narrowing towards the bow and stern of the hull. In general, however, the frames are of substantially the same irregular polygonal shape, though the frames at the bow and the stern portion of the hull have their lower portions tapered to a greater extent and narrower than the frames at the mid-ship portion of the hull.

The notches of the frames 1 receive frame members 2 which extend longitudinally of the hull from stem to stern thereof. Each of the frames 1 is provided, in its lower end, with a notch or recess which receive a keel 3, the forward portion of which is curved upwardly to provide a stem 4. A stern post 5 extends upwardly from keel 3 and has its upper portion curved upwardly and outwardly to extend beneath the overhang of the stern, and provided with a bearing 6 for a rudder stock support, this bearing being disposed above and in alignment with a rudder pintle bearing 7 formed at the stern end of keel 3, which extends beyond post 5.

The frame members 2, as well as the keel 3 and stem 4 are of circular cross section and tubular construction. Members 2 are welded to frame 1 and to the stem 4 and stern post 5. This provides a light but very strong frame for the hull. The stern post 5 is also welded to the keel 3 and is provided with a propeller shaft bearing 8. Referring more particularly to Figs. 2, 5 and 7, the welding between the frame 1 and the frame members 2 is indicated at 9.

After the hull frame has been constructed covering or skin plates 10 and deck plates 11 are applied thereto. As will be noted more clearly from Figs. 5 and 7, the recesses or notches at the angles of the frame 1 are of such depth that two plates disposed at opposite sides of any one of the frame members 2 will seat upon the adjacent straight edge por-

tions of the frame 1, the edge portions of these plates seating upon member 2. By having the members 2 of rounded or circular cross section, the edge portions of the plates seating on this member are disposed at a tangent thereto and there is no difficulty encountered in obtaining proper contact of the plates with the frame members. I thus avoid delay in accurately fitting the plates to the frame members 2 such as would occur, in many instances, if frame members of other than round or circular cross section were employed.

To facilitate application of the plates to the frame structure I employ means whereby these plates can be clamped firmly in position during the welding operation, the clamping means being then removed and welding of the plates completed. In Fig. 5 I have shown a deck plate 11 and a cover or side plate 10 seated upon the upper and the side edges, respectively, of a belt frame 1. To hold these plates in position I weld screw studs 12 to the frame member 2 at suitable intervals. A clamping plate 13 shaped to contact the outer faces of plates 10 and 11, is then placed upon the stud 12 and is forced toward frame 1 and members 2 by a nut 14 screwed onto the stud. In this manner the two plates are clamped firmly in position and these plates are then welded, as at 15, to the frame 1. The edges of the plates which seat upon the member 2 are then welded to this member at 16, the welding being omitted at the clamps. The clamping plates 13 are then removed from studs 12 and these studs are chipped off of the frame member 2. The welding of the plates to the frame member is then completed, the plates being welded throughout the entire length thereof. In Fig. 7 I have illustrated two side plates 10 with their adjacent edges seating upon a frame member 2 and welded thereto and to the belt frame 1. These plates 10 are secured in position, during the welding operation, by a clamping plate 17 mounted upon a screw stud 12 in the same manner as the plates 10 and 11 are held in position. The forward edges of the foremost side plates at the bow are welded to the stem 4 and may be clamped in position during the welding operation in the manner above described.

The lower edges of the lowermost plates are welded to the keel 3, being suitably clamped in position during the welding operation, as above. The rearward or sternmost edges of the side plates beneath the overhang are suitably fitted about the stern post 5, certain of these plates being fitted about the bearing 8, and are welded to the stern post. The hull thus produced is relatively light but possesses great strength and can be fabricated at much lower cost than hulls in which the frame elements and the plates are secured together by riveting.

The plates 10 are secured together at their ends by butt welding or by lap welding, as preferred. The deck plates 11 are suitably welded to frames 1 and the uppermost frame members 2, as described, and the edges of these plates are secured together by butt welding. Preferably electric welding is employed for securing the various elements of the frame and the plates together, though this is not essential as any suitable means of welding may be employed.

I preferably employ belt frames 1 which are of substantially irregular polygonal outline and are defined by straight edge portions disposed in angular relation. These frames can be fabricated at appreciably less cost than frames having faired and curved lines to correspond to the cross section of a ship hull as commonly constructed under present practice.

By employing, with these frames, the rounded or circular frame members 2 I obtain a combination of straight edges and plates seating thereon and tangent to the frame members, whereby the securing of the plates to the framework of the hull is greatly facilitated. I do not, however, intend to limit myself to the one form of belt frame illustrated and described. In its broader aspects, my invention contemplates the use of belt frames of any suitable or desired shape in conjunction with frame members secured thereto by welding and plates secured to the frames and the frame members by welding. I also contemplate having the covering or side plates 10 of proper length to have the ends thereof seating upon the belt frames and welded thereto.

What I claim is:

1. In combination in a hull construction for ships, a keel of circular cross-section comprising the stem of the hull, a plurality of transverse belt frames welded to the keel, longitudinal frame members shaped about the frames and welded thereto, said members being of circular shape, and covering plates having their edge portions seating upon the frame members and the keel and stem, said plates being welded to the frames and to the frame members and the keel and stem.

2. In combination in a hull construction for ships, a keel of circular cross-section comprising the stem of the hull, a plurality of transverse belt frames, a stern post of circular cross-section secured to the keel, longitudinal frame members of circular cross-section shaped about the frames and welded thereto and to the keel and stem and the stern post, and covering plates having their edge portions seating upon said members and upon the keel and stem and the stern post, said plates being welded to the frames and to the frame members and the keel and stem and the stern post.

3. In combination in a hull construction for ships, a keel of circular cross-section comprising the stem of the hull, a plurality of transverse belt frames, a stern post of circular cross-section secured to the keel, longitudinal frame members of circular cross-section shaped about the frames and welded thereto and to the keel and stem and the stern post, and covering plates having their edge portions seating upon said members and upon the keel and stem and the stern post, said plates being welded to the frames and to the frame members and the keel and stem and the stern post, the keel being extended sternward beyond the stern post and shaped to provide a rudder pintle bearing, said post being shaped to provide a propeller shaft bearing and having a bearing for the rudder stock support.

4. In combination in a hull construction for ships, a plurality of transverse belt frames of polygonal shape, the sides of said frames being straight and flat and the frames being provided with notches at the exterior angles thereof, longitudinal frame members fitting into said notches and shaped about and welded to said frames, the outer portions of the frame members being rounded and substantially flush with the sides of the frames, and covering plates seating flat against the sides of the frames and welded thereto, the upper and lower edges of the plates seating upon the outer faces of the frame members and being welded thereto.

5. In witness whereof, I hereunto subscribe my name this 22 day of November, 1928.

EDWIN B. WHEELER.
